CLAIM

I claim the ornamental design for a stanchion cover, as shown and described.

DESCRIPTION

FIG. 1 is a front elevational view of stanchion cover according to the present invention, with the side and back and views being the same as the front view; and, FIG. 2 is a front elevational view of the stanchion cover of FIG. 1 showing the cover received over a stanchion that extends out of the ground, the ground and the stanchion forming no part of the present invention.
